US0D1028649S

(12) **United States Design Patent** (10) **Patent No.:** **US D1,028,649 S**
(45) **Date of Patent:** **** May 28, 2024**

(54) **PLANT-CLIP**

(71) Applicants: **Jikke Roos Amalia de Jong**,
Honselersdijk (NL); **Marille Marie Isora de Jong**, Honselersdijk (NL)

(72) Inventors: **Jikke Roos Amalia de Jong**,
Honselersdijk (NL); **Marille Marie Isora de Jong**, Honselersdijk (NL)

(**) Term: **15 Years**

(21) Appl. No.: **35/517,319**

(22) Filed: **May 10, 2023**

(80) **Hague Agreement Data**

Int. Filing Date: **May 10, 2023**

Int. Reg. No.: **DM/228981**

Int. Reg. Date: **May 10, 2023**

Int. Reg. Pub. Date: **May 26, 2023**

(51) **LOC (14) Cl.** **08-01**

(52) **U.S. Cl.**

USPC **D8/1**

(58) **Field of Classification Search**
